ATTORNEY

UNITED STATES PATENT OFFICE.

BIRGER EKENBERG, OF NEW YORK, N. Y.

FEED-WATER HEATER.

SPECIFICATION forming part of Letters Patent No. 773,132, dated October 25, 1904.

Application filed October 1, 1903. Serial No. 175,327. (No model.)

To all whom it may concern:

Be it known that I, BIRGER EKENBERG, a subject of the King of Sweden and Norway, residing in the city of New York, borough of Brooklyn, in the county of Kings and State of New York, have invented a certain new and useful Improvement in Feed-Water Heaters, of which the following is a specification.

The invention relates to traction or self-propelling road-engines, and particularly to that class in which steam is employed for the motive power.

An important object of the invention is to provide a motor-vehicle adapted for heavy service, such as transporting heavy loads or drawing loaded wagons, plows, and performing analogous duties, also adapted to serve as a portable engine for hoisting and winding and for driving threshers, saw and other mills, and like machinery, in which the hot portions of the apparatus are so arranged relatively to the water-tank and its connections as to raise the temperature of these parts sufficiently to insure them from freezing, and thus permit the engine to be used successfully during periods of extreme low temperature.

The invention consists in certain novel features and arrangements of parts by which the above objects are attained, to be hereinafter described.

The accompanying drawings form a part of this specification and show the invention as it has been carried out.

Figure 1 is a side elevation showing the traction-engine complete and a portion of a wagon or truck drawn thereby. Fig. 2 is a plan or top view with the cover or canopy removed. Fig. 3 is a corresponding view with portions of the floor or platform omitted to show the parts beneath. The remaining figures are on a larger scale and show details of the construction. Fig. 4 is a front elevation, partly in vertical section, showing the front or steering wheel and its saddle and connections.

Similar letters of reference indicate the same parts in all the figures.

The main frame of the vehicle is composed of steel I-beams carrying the engine, boiler, water-tank, driving and hoisting mechanism

and other equipments supported on two driving-wheels at the rear and a single steering-wheel at the front. The I-beams or rails at the sides are marked A and extend parallel with each other from the rear to a line forward of the mid-length, where they are bent inwardly toward the center line, as at A', and thence extend again longitudinally parallel and in the same plane to the front, as at A''. The rails are connected by transverse beams 60 of the same cross-section lying in the same plane with the rails and joined thereto by gusset-pieces, as usual. The beam at the rear is marked A³, another at about the mid-length A⁴, another A⁵ at the line of the bending of 65 the side rails, and two shorter beams A⁶ A⁷ at the front. The gussets are marked A⁸.

The motor B, shown as a vertical compound steam-engine, is mounted with its shaft B' transversely of the frame upon the frame members or beams A⁴ A⁵. The boiler C is of the vertical self-feeding type and is supported by lugs attached thereto and resting on the members A' A' A⁶ in the space inclosed by these members and the member A⁶.

The hoisting-drums D' D² and their shaft D extend transversely of the frame at the rear and are supported in bearings bolted to the under faces of the members A A, and the whole is carried on a rear driving-shaft E, journaled in boxes E', received in vertical yokes A⁹, bolted to the members A A, and having two traction-wheels E² E², and on a steering-wheel F² at the front, mounted in a rotatable yoke or saddle F'. The latter has 85 a circular head F, provided with a circular steel plate or ring f, having an annular groove, in which is received a series of hardened-steel balls f', serving as an antifriction-support for the forward portion of the vehicle, the 90 load being transmitted thereto through a casting G of circular form, having a ring grooved on the under face to match to the series of balls and having four arms G' securely bolted to the frame members A² A² A⁶ A⁷. A pintle 95 F³ from the head F extends through the center of the casting G and is squared to receive the boss F⁴ of a segment F⁵, having its periphery toothed to match to the threads of a worm F⁶, by which the vehicle is steered. ing-screw through the boss holds the segment against loosening or jarring off.

The shaft or axle F⁸ of the steering-wheel F² is journaled in boxes F⁹, arranged to slide 5 in the vertical ways or jaws F¹⁰ of the yoke and supports the latter, with the front end of the vehicle, on helical springs F¹¹ between the boxes and yoke.

The main shaft of the engine extends across 10 just above the frame and is supported in three bearings on the frame members A A and a short intermediate member A¹⁰. The shaft is in two parts, connected by a universal joint at B², and carries on one side of the vehicle an 15 overhung pulley B³ and on the other a beveled gear-wheel B⁴, from which power for the winding and hoisting mechanism is taken. The shaft B' also carries a crank B⁵, operating the feed-pump, and a pinion B⁶ splined to 20 receive a feather on the shaft and to slide axially thereon into and out of mesh with a gear-wheel H' on a counter-shaft H below the shaft B and supported in bearings on the under faces of the members A A. The shaft H 25 carries a sprocket-wheel H², on which runs a sprocket-chain H³, preferably of the Reynolds "silent" type, partially encircling a corresponding but larger sprocket-wheel E³, forming part of the differential gear on the 30 rear or driving axle E. Power from the engine is transmitted through the sliding pinion B⁶ to the counter-shaft H and thence by the wheels H² E³ and chain H³ to the traction-wheels E² E² on the shaft E. The pinion B⁶ 35 is thrown into and out of mesh by a suitable lever B⁷ and connections therefrom. (Not shown.)

The forward end of the vehicle is rounded and the space in front of the boiler occupied 40 by a water-tank I of large capacity resting on a floor A¹¹, supported above the steering-segment and overhanging the frame on each side. The tank is covered with a flooring I', which may be provided with an asbestos or other 45 non-conducting lining to protect the tank from cold and is equipped with filling-holes I², as required. The top of the boiler C projects a little above the tank and products of combustion are led through a curved pipe C' 50 to a curved flue C², traversing the tank and finally escaping through a stack C³. The heat thus supplied is absorbed by the water in the tank and the temperature kept sufficiently high to prevent freezing while the boiler is 55 in service. Fuel is supplied through a central opening having a cover C⁴, and at the lower end of the boiler is an additional fire-door and ash-pit door, (marked C⁵ and C⁶.)

A floor A¹² at a higher level than the floor 60 A¹¹ extends rearwardly from the water-tank to the back of the vehicle, constituting the main deck thereof. It is cut away to receive the boiler and engine, and in the immediate vicinity of the boiler is a lower floor or deck 65 A¹³, supported on transverse partitions form-

ing a closed box or compartment containing the feed-pump J and feed-water heater K and their connections, receiving heat from the boiler and inclosed steam-pipes.

The boiler is located centrally, with the engine on one side and a driver's seat L on the other. Immediately in front of the driver is the tiller-wheel F¹³ on a vertical shaft F¹⁴, transmitting motion through the beveled gears F¹⁵ to the horizontal shaft F¹⁶, on which is the 75 worm F⁶, in mesh with the segment F⁵, as above described.

Steam from the boiler passes through a pipe C⁷, controlled by a stop-valve C⁸ and a throttle-valve C⁹, located at the left of the driver 80 within easy reach to the engine, and after doing its work in the high and low pressure cylinders passes through the exhaust-pipe C¹⁰ to the feed-water heater K and thence through the curved pipe C' and flue C² to the stack. 85

The feed-pump J runs continuously while the engine is in motion and draws water through the pipe J' from the tank and delivers it through the pipe J² to the feed-water heater. After traversing the latter it returns 90 through a pipe K' and is fed to the boiler through a branch K², when required, or if the boiler is sufficiently supplied passes through the branch K³, controlled by the valve K⁴, to the tank and serves by circulating therein to 95 raise the temperature. The valve K⁴ is placed within easy reach of the driver outside of the closed compartment in which the water-pipes are inclosed.

At the left of the driver below the throttle-valve is a brake-operating shaft M, having a horizontal crank-handle M', by which it may be turned. At the lower end is a screw (not shown) connecting it to the jaws of a forked lever secured to a transverse rocking shaft M², 105 on which are carried two arms M³, equipped with brake-shoes M⁴, adapted to bear frictionally against the smooth central portions of the peripheries of the driving or traction wheels E² E². The remaining circumferential portions of the wheels are roughened by diagonal lands and grooves adapted to take hold in soft ground and to ride over hard-surfaced roads without roughening or injuring them. The action of the screw permits the 110 brake to be applied with great force by the expenditure of but little power and has the additional advantage of holding the shoes in or out of contact without employing other locking devices. 115

The lever B⁷ shown just in front of the driver's seat controls the sliding pinion B⁶, described above, by which the power may be shifted from the propelling mechanism to condition the engine to serve either in driving other machinery through a round or flat belt running in the groove or on the face of the pulley B³ or in winding or hoisting by the drums D' D² and derrick R. 125

Motion is imparted to the winding-drums 130

through the beveled gear-wheel B^4 on the main shaft and a corresponding pinion D^8 on a sleeve D^4 , inclosing the end of a rearwardly-extending shaft D^5 , supported in suitable bearings and equipped with a clutch D^6 , operated by a lever D^7 at the right of the driver and permitting the shaft D^5 to be revolved or released when required. The rear end of this shaft carries a worm D^8 , engaging a worm wheel D^9 , secured on the transverse hoisting or drum shaft D . The main hoisting-drums $D' D'$ are loosely mounted on this shaft and are caused to revolve therewith by a double cone P on a squared central portion of the shaft and thrown to either side to engage in correspondingly-shaped cavities in the drums D' by a rock-shaft P' , operated by a hand-lever P^2 , located in the center of the driver's space and at the left of the seat. The rock-shaft has a pair of arms P^3 engaging pins on a ring received in a circumferential groove between the cones, by which the latter are moved on the shaft D to engage the drums.

The drums are held against revolving in the direction of the strain by pawls engaged in ratchets P^6 on the drums and disengaged by foot-levers P^7 adjacent to the lever P^2 , controlling the cones.

The hoisting-derrick comprises a mast R , set in a suitable step or socket R^2 on the rear frame member A^3 and guyed from the top to the roof-supporting stanchions A^4 at each side at the front by ropes R^3 , equipped with snatch-blocks or other means of hauling them taut, and a boom R' , pivoted in a bracket near the base of the mast and having at the outer end an eye R^4 , in which is secured a rope R^5 , running over a pulley R^6 at the top of the mast to one of the drums, by which the boom is lifted and swung, and a yoke R^7 , having a hook to which is attached the hoisting-rope R^8 , forming a bight, as usual, containing a hooked block for the load and running over a pulley R^9 , set in the end of the boom, and thence to one of the drums. Each of the main portions D' of the latter is adapted to receive a rope to be wound thereon, and the smaller portions D^2 , turning with the shaft D , are adapted to receive one or more turns of a rope held in frictional contact therewith by strains

on the free end. The derrick may be removed when desired by loosening the guys and unstepping the mast with its boom and may be carried alongside the vehicle in suitable loops or slings. (Not shown.)

55

S is an eye or coupling-head adapted to receive a link S' , by which a trailer or other object to be moved, as the wagon T , Fig. 1, may be attached.

The provisions for imparting heat to the water-tank and protecting the connections therefrom enable the machine to be used in all weathers and permit sawing, threshing, winnowing, and other winter operations to be successfully performed.

65

I claim—

1. In a motor-vehicle, a water tank and boiler, and a smoke-flue from the furnace of said boiler traversing the tank extended into the stack and serving to raise the temperature of the water therein, the smoke-flue having reverse curves.

70

2. In a motor-vehicle, a water-tank, boiler, and engine, a flue from the furnace of said boiler traversing the tank and extended into and emptying into the stack, an exhaust-steam pipe entering said flue from said engine, said flue being reversely curved and serving to raise the temperature of the water in said tank by the passage therethrough of products of combustion and exhaust-steam.

75

3. In a motor-vehicle of the character set forth, a water-tank, boiler, and engine, a curved pipe and a reversely-curved smoke-flue from the furnace of said boiler traversing the tank, a closed compartment inclosing a portion of said boiler, a feed-pump, a feed-water heater and water connections from said tank all inclosed in said compartment, an exhaust-steam pipe from said engine to said feed-water heater, and an exhaust-steam pipe from said heater to said flue.

80

In testimony that I claim the invention above set forth I affix my signature in presence of two witnesses.

BIRGER EKENBERG.
